S. E. BARTOLD

CALENDAR PAD FASTENER

Filed July 24, 1924

Patented Apr. 7, 1925.

1,532,863

UNITED STATES PATENT OFFICE.

SAMUEL E. BARTOLD, OF CHICAGO, ILLINOIS.

CALENDAR-PAD FASTENER.

Application filed July 24, 1924. Serial No. 728,033.

To all whom it may concern:

Be it known that I, SAMUEL E. BARTOLD, a citizen of the United States, residing at Chicago, in the county of Cook and State 5 of Illinois, have invented new and useful Improvements in Calendar-Pad Fasteners, of which the following is a specification.

This invention relates to fasteners for calendar and memorandum pads and consists in the matters hereinafter described and claimed.

In the accompanying drawings—

Fig. 1 is a perspective view of a wall calendar with pad applied by the fastener 15 of my invention;

Fig. 2 is an enlarged fragmentary rear view of the same;

Figs. 3 and 4 are fragmentary vertical sectional views taken on line 4—4 of Fig. 2; 20 Fig. 3 showing the fastener open and Fig. 4 showing the fastener closed; and

Fig. 5 is a perspective view of the fastener.

The calendar has a back 1 preferably flat and made of cardboard, metal, or other material. On its face, the back 1 may carry such advertising or other display as may be desired, and it is provided with an eyelet 2 at its upper edge for hanging the calendar up on a wall.

Leaves or sheets 3 in pad or pack form are held on the front face of the back 1 by a fastener 4 of my invention. This fastener is made from a single piece of relatively stout bendable wire or other material, and 25 is bent to have the shape shown in Fig. 5. As there shown, said fastener has a substantially straight mid-portion 5 and joining end sections on the same side thereof and transverse thereto. The end sections are bent to have loops 6, 6 at their outer ends and transverse intermediate portions 7, which join the loops to the mid-section 5. The loops 6 and sections 7 are transverse to each other, as shown, and provide the fastener with spaced 40 members having parts to engage the board and calendar pad, respectively.

The fastener is applied to the back 1 from the rear by passing the outer ends of the loops 6 through spaced apertures 8, 8 in the back 1. After the loops are brought in front of the back with their arms *a*, *b* extending upward, as shown in Fig. 3, the sheets or leaves 3, in pad or pack form, may be readily applied thereto by inserting the 50 loops through the apertures 9, 9 in the sheets. At this time, the end sections 7, 7

of the fastener project rearward from the back with the mid-bar 5 spaced therefrom, as shown in Fig. 3.

Turning the mid-bar 5 down against the 60 back 1 raises the loops 6 in front of the back and in position with the sheets 3 suspended from the lower arms *a* of the loops. The upper arms *b* of the loops are above the sheets and, being shorter than the lower 65 arms, terminate at or abut against the front face of the back and prevent the sheets from slipping off the loops when they are turned up on the upper arms, as shown in Fig. 4.

The fastener 4 is locked on the back 1 by 70 having its mid-bar 5 engaged by a clip 10 carried by the back 1 on its rear side. This clip is so positioned that the mid-bar 5 must be flexed or sprung downward to engage under it, as shown by dotted lines in Fig. 2. 75 This places the required tension on the fastener 4 to hold it tightly on the back and prevent the pad or pack 3 from rocking the fastener to open the loops 6.

The sheets 3 may be left blank on one side 80 and be printed on the other with the days of the month, etc., so that as they are turned on the loops, a sheet either below or above, as the case may be, will display the day of the month while another sheet may be 85 used for notes or memoranda. The apertures 8 may be eyeleted, as shown.

With the fastener of my invention, the back 1 and fastener may be retained from year to year and new calendar pads be 90 applied, instead of discarding the entire back and fastener, as now required with calendars using binding posts or bolts to secure the pads thereto. By my invention, the old pad if retained may be easily and quickly 95 removed by releasing the mid-bar 5 from the clip 10 and turning the loops 6 into position for taking off the pad. Thereupon a new pad may be applied. The fastener 4 being in one piece facilitates engaging the two 100 spaced openings in the pad and back, and enables the fastener and pad to be quickly and easily applied to each other as well as to the back. My fastener enables the back 1 to be used for a longer time, thus gaining 105 more service out of the advertising thereon. In addition, the cost of furnishing calendars is lessened because only the pads need be furnished as the backs and fasteners are retained.

When used for a desk calendar and memorandum pad, the back 1 may be provided

2
with a support to hold it in an inclined position when laid on a desk or the like.

The details of structure shown and described may be variously changed and modified without departing from the spirit and scope of my invention.

I claim as my invention:

1. The combination with a back and a pad of calendar or other sheets therefor, of a one-piece wire fastener bent to have a mid-portion and end portions transverse thereto, with the end portions bent to have transverse parts, said fastener being applied to the back with certain of the parts of the end portions extending outward through the back and through holes in the pad to support the same, and with the mid-portion and the other parts of the end portions to the rear of the back, said last named parts extending along the back from the holes through which the first parts extend, and means carried by the back and engageable with said mid-portion for detachably locking the fastener to the back.
2. The combination with a back and a pad of calendar or other sheets therefor, of a one-piece wire fastener bent to have a mid-portion and end portions transverse thereto, with the end portions bent to have loops at their outer ends and transverse intermediate portions joining the loops to said mid-portion, said fastener being applied to the back with its loops in front of the same and extending through the back and through holes in the pad to support the latter, said intermediate and mid-portions being to the rear of the back, and a clip on the back and engageable with said mid-portion on springing the same under the clip for detachably locking the fastener to the back.
3. The combination with a back and a pad of calendar or other sheets therefor, of a one-piece wire fastener bent to have a mid-portion and end portions transverse thereto, with the end portions bent to have loops at their outer ends and transverse intermediate portions joining the loops to said mid-portion, said fastener being applied to the back with its loops in front of the same and extending through the back and through holes in the pad to support the latter, said intermediate and mid-portions being to the rear of the back, and a clip on the back and engageable with said mid-portion on springing the same under the clip for detachably locking the fastener to the back.
4. The combination with a back and a pad of calendar or other sheets therefor, of a one-piece wire fastener bent to have a mid-portion and end portions transverse thereto with the end portions bent to have loops at their outer ends and transverse intermediate portions joining the loops to said mid-portion, said fastener being applied to the back from the rear with its loops in front of the same and extending through the back and through holes in the pad to support the same, said intermediate and mid-portions being to the rear of the back, and a clip on the back and engageable with said mid-portion on springing the same under the clip for detachably locking the fastener to the back, said loops having parts extending to the back over the adjacent edges of the pad and terminating at said back to place the fastener under tension when engaged with said clip.

In testimony that I claim the foregoing as my invention, I affix my signature this 19th day of July, 1924.

SAMUEL E. BARTOLD.
